UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SMASH PROTECTOR FOR LOOMS.

Application filed January 5, 1923. Serial No. 610,792.

To all whom it may concern:

Be it known that I, WILLIAM W. ROBERTSON, a citizen of Canada, residing at Worcester, in the county of Worcester and State of Massachusetts, have invented a new and useful Smash Protector for Looms, of which the following is a specification.

This invention relates to a smash protector particularly designed for use on certain 10 types of carpet looms on which one lay end has a motion independent of the remaining portions of the lay.

It is the general object of my invention to provide a construction in which the protector will be operative in every relative 15 position of the lay and movable lay end.

In the preferred embodiment of my invention I provide a protecting device or dagger on the main lay and a controlling 20 device therefor mounted on the movable lay end, these parts co-operating to indicate presence or absence of the shuttle in the shuttle box on the movable lay end in every relative position of the parts.

25 My invention further relates to arrangements and combinations of parts which will be hereinafter described and more particularly pointed out in the appended claim.

A preferred form of the invention is 30 shown in the drawings, in which

Fig. 1 is a side elevation of parts of a loom embodying my improvements;

Fig. 2 is a sectional plan view taken along the line 2—2 in Fig. 1; and

35 Figs. 3 and 4 are diagrammatic plan views, showing the relation of the parts when in different positions.

Referring to the drawings, I have shown certain parts of a loom including a loom 40 frame 10 supporting a rock shaft 11 on which are mounted lay swords 12 and a lay end support 13. The swords 12 support the usual lay 14 having a shuttle box 15 at one end thereof. Protecting devices 16 of the 45 usual type are mounted on a rock shaft 17 carried by the lay 14 and these devices are adapted to engage yielding stop plates 18 pivoted at 19 on the loom frame 10.

An arm 20 extends rearwardly from the 50 plate 18 and a very heavy coil spring 21 is connected between the free end of the arm 20 and a bracket 22 secured to the loom frame 10. When the protecting devices 16 engage the stop plates 18 at the opposite sides of the

loom the springs 21 permit the plates to 55 yield slightly as the lay is brought to rest, thus reducing materially the shock which would be occasioned by striking a rigid stop.

A lay end 24 is mounted on the support 13 and is provided with a shuttle box preferably comprising a fixed front box plate member 25, a movable front box plate member 26, a fixed back box plate 27 and a pivoted binder 28. A protector finger 29 is secured to a short shaft 30 pivotally 60 mounted on the lay end 24 and having an arm 31 secured to the opposite end thereof. The arm 31 is provided with a roll 32 positioned to engage an arm 33 extending rearwardly from the shaft 17 on which the protecting devices 16 are mounted.

The upper engaging surface of the arm 33 is preferably formed of an arc struck from the axis of the shaft 11. A spring 40 causes the arm 33 to yieldingly engage the 65 roll 32 and thereby maintains the finger 29 in contact with the binder 28. The spring 40 also acts to move the protecting device 16 into position to engage the stop plate 18 when both shuttle boxes are empty.

Having thus described my invention, it will be seen by reference to Figs. 3 and 4 that the roll 32 contacts with the upper curved surface of the arm 33 in every relative position of the lay 14 and lay end 24, 85 whether the parts are in the usual running relation shown in Fig. 3 or in the separated "beat-up" relation shown in Fig. 4. It will also be seen that the lay and lay end can move forward and rearward, either separately or together, without material change in the operative relation of these parts.

Having thus described my invention it will be seen that I have provided a very simple construction by which different parts 95 of the protecting mechanism may be mounted upon relatively movable members while at the same time preserving a co-operative relation of the parts under all conditions.

It will be further evident that changes and modifications can be made in my invention by those skilled in the art and I do not wish to be limited to the details herein disclosed otherwise than as set forth in the 105 claim but what I claim is:—

In a loom, a lay mounted to swing about a fixed pivot, a lay end mounted to swing

with said lay about said fixed pivot and also constructed to be at times positioned independently of said swinging lay, a protector device on said lay, a shuttle indicating device on said lay end, a single spring effective to actuate said protecting device and said indicating device in every relative position thereof, separate parallel rotatable shafts on which said protecting device and said indicating device are supported, and connections between said shafts operative in every relative position of the lay and lay end, said

connections including a rearwardly projecting arm on the protector shaft on the lay and a rearwardly projecting member on the indicating shaft on the lay end, said member engaging said arm when said lay and lay end are moving together and also when said lay and lay end are independently positioned and relatively movable.

15

In testimony whereof I have hereunto affixed my signature:

20

WILLIAM W. ROBERTSON.
